UNITED STATES PATENT OFFICE.

EDWARD W. BUSH, OF ARMSTRONG, MISSOURI.

WASHING-MACHINE.

SPECIFICATION forming part of Letters Patent No. 289,615, dated December 4, 1883.

Application filed April 27, 1883. (No model.)

To all whom it may concern:

Be it known that I, EDWARD WALTER BUSH, of Armstrong, in the county of Howard and State of Missouri, have invented a new and 5 Improved Washing-Machine, of which the following is a full, clear, and exact description.

The object of the invention is to produce such combinations of parts as will facilitate the application of rubbing devices to an ordinary 10 wash-tub. This combination will first be described in connection with the drawings, and all else which is necessary to a full understanding of the invention, and then pointed out in the claim.

15 Reference is to be had to the accompanying drawings, forming part of this specification, in which similar letters of reference indicate corresponding parts in all the figures.

Figure 1 is a cross-sectional elevation of my 20 improved washing-machine. Fig. 2 is a sectional plan view of the same on the line *x x*, Fig. 1. Fig. 3 is a detail elevation and sectional view of the device for holding the false bottom in the tub.

25 On the upper surface of the bottom A of a wash-tub, B, of the usual construction, two cleats, C, are fastened, under the projecting parts of which the rabbeted end of a cross-bar, D, of a frame, D', can be passed, which 30 frame is to rest on the bottom of the tub, and is held in place by the cleats. On the frame D' a false bottom, E, is fastened, which fits closely in the tub, and is provided on its upper surface with a series of radial ribs or 35 ridges, F, of different lengths. Between the ridges the false bottom E is provided with numerous apertures, G. On the middle of the false bottom E an upwardly-projecting rod, H, is fastened, the upper end of which passes 40 loosely through an eye, J, formed at the upper united ends of two braces, K, provided at their lower ends with forks K', adapted to be passed on the upper edge of the tub. The upper end of the rod is thus held so that it will always

45 remain vertical. A sleeve, L, surrounding the rod H, is formed on the upper united ends of two arms, M, having their lower ends secured to the upper surface of a revolving disk, N, fitting in the tub, and provided on its under 50 surface with radial ridges F', like the ridges F of false bottom E. The rotating rubbing-

disk N is provided with numerous apertures, G'. The rod H is provided with a longitudinal feather or spline, P, and the collar or sleeve L, and a washer, Q, on the upper surface of 55 the disk N, and the disk are provided with vertical grooves R, through which the said spline can pass. The collar or sleeve L is provided with a handle, S. On the inner side of the tub latches T are pivoted, which can be 60 passed into recesses in the edges of the false bottom to lock the same in place and prevent the same from turning.

The operation is as follows: The clothes to be washed are spread evenly on the false bottom E, and the disk N is lowered on the clothes, 65 the tub is partly filled with water, and the disk N is rocked to and fro in the horizontal plane by means of the handle S, whereby the clothes will be thoroughly rubbed and washed. The 70 dirt washed from the clothes passes, with the heavy dirty water, through the apertures G in the false bottom E, and collects in the bottom A below the false bottom, and cannot again mix with the water, so that the suds will be 75 cleaned for receiving the next tub-full of clothes. The disk N is held on the clothes by turning the collar L in such a manner that the spline P can pass up through the groove R in the collar. The upper edge of the collar will then be 80 below the lower end of the spline, and if the collar is turned the spline prevents it from rising. Care must be taken not to turn the collar to such an extent that the spline can pass through the groove R. In a like manner the 85 collar can be held above the spline. If the disk N, (the braces K having been previously removed from the tub B and shaft P, when the collar L is grasped by the hand, and by pulling upward thereon the said disk, with its 90 adjunctive parts, is lifted out of the tub off the shaft H,) is to be removed, the same and the collar L are turned until the spline P can pass through the slots R in the collar and in the washer Q.

95 After the machine has been used, all parts can be easily and rapidly taken from the tub, which can then be cleaned thoroughly.

The confined air can escape through the apertures G' in the rubbing-disk, thus allowing 100 the weight of the disk to press more forcibly on the clothes.

I am aware that ribbed rubbers—one rocking or rotary and the other stationary—are very old in washing-machines; also, that they have been perforated, and the lower one made 5 to form a false bottom elevated above the true bottom of the tub; but

What I do claim as new and of my invention is—

In a washing-machine, the combination, with 10 a wash-tub, of a stationary rubber or false bot-

tom, E, having a central rod, H, with spline P, and a rocking rubber having the collar L, with groove R, whereby the rocking rubber may be held at the desired distance above the stationary one, as described.

EDWARD W. BUSH.
